United States Patent Office.

JAMES ARMSTRONG, OF BUCYRUS, OHIO.

Letters Patent No. 98,009, dated December 21, 1869.

IMPROVED WASH-BOILER.

The Schedule referred to in these Letters Patent and making part of the same.

To all whom it may concern:

Be it known that I, JAMES ARMSTRONG, of Bucyrus, in the county of Crawford, and State of Ohio, have invented a new and useful Improved Wash-Boiler; and I do hereby declare that the following is a full, clear, and exact description thereof, reference being had to the accompanying drawing, in which—

Figure 1 is a plan view, with the cover removed; Figure 2, a longitudinal vertical section, taken in the line *x x* of fig. 1; and

Figures 3, 4, and 5 are perspective views of the internal parts of the boiler.

Like letters designate like parts in all the figures.

The nature of my invention consists in the peculiar construction of the several parts used in the interior of the boiler, which may be made of wood or any other suitable material.

To enable those skilled in the art to make and use my invention, I will proceed to describe its construction and operation.

In the drawing—

A represents the exterior portion of the boiler, which is of the ordinary construction.

B is a false bottom, which is placed inside the boiler. This is formed of two flat pieces secured together by means of side pieces *a a*, which extend down below the flat pieces *B*, and rest on the bottom of the boiler, thereby leaving a water-space between the bottom of the boiler and the false bottom *B*.

The two flat parts of the bottom *B* are inclined from their outer ends downward, but do not meet, thereby leaving an open space *b*, for the passage of water from above to the water-space below.

On the upper side of the false bottom are grooves *c*, to facilitate the passage of water to the opening *b*.

Across each end of the boiler are upright pieces *C C*, which are connected to the bottom *B* by means of lugs *d*, on their lower ends, parts of which fit into recesses *e*, in the ends of the bottom *B*, and the ends of the lugs extend under the said bottom.

In the inner sides of the upright pieces *C C* are grooves *f*.

D is a cover, which is placed over the clothes after they have been put in the boiler.

On one end of this cover is a sliding piece *E*, attached to which is an arm, *g*, in which is a slot, *h*, through which a pin is driven into the cover *D*.

After the clothes have been placed in the boiler, to hold the cover *D* in its position, insert the solid end into one of the grooves *f* in one of the end pieces *C*, then move the sliding piece *E* into one of the grooves in the other end piece *C*.

This is held there by a pin, *i*, placed in the cover *D*, at the rear end of the arm *g*.

In the cover *D* are slots, which may be made either longitudinally or transversely, to allow the water to pass down through the clothes.

Its operation is as follows:

The clothes having been placed in the boiler, and it supplied with a sufficient quantity of water, when that in the water-space under the false bottom is heated sufficiently to make it boil, it passes up the spaces at each end of the boiler, and flows over the end pieces *C*, on to the cover *D*, down through the slots and clothes, and through the opening *b*, in the bottom *B*, back into the water-space, thus keeping up a constant circulation of water.

Having thus fully described my invention,

What I claim, and desire to secure by Letters Patent, is—

1. The bottom *B*, when constructed substantially as and for the purpose shown and described.

2. The removable adjustable top *D*, when constructed substantially as shown and described.

3. The combination of the bottom *B*, top *D*, and end pieces *C C*, when constructed and arranged substantially as shown and described.

Witnesses: JAMES ARMSTRONG.

A. SUMMERS,
FRANK'N ADAMS.
